5 Claims. (Cl. 179—25)

1

The present invention relates to arrangements for cross-bar switches, more particularly to a system for obtaining, by means of current impulses or current break, successive operation of the selecting magnets in cross-bar switches, for example for numerical setting.

In previously known systems of that kind, contact spring groups operated directly by the selecting bars are used in order to obtain necessary contact functions for the setting. Such contact spring groups have certain disadvantages. It is among other things difficult to place the contact spring groups adequately from a dust protection view point. Further, each selecting bar is operated by two selecting magnets and turned to the one or the other side by an armature common to the two selecting magnets, different contact spring groups being actuated by the two magnets. By releasing the armature after an operation to one side, it may turn over to the other side, causing an improper operation of the contact spring set, that is operated by turning the selecting bar to said other side. Besides, they are comparatively costly.

By this invention said contact spring groups will be entirely disposed of, as all contacts necessary for a successive operation of the selecting magnets are actuated by an operating magnet and only indicated by the selecting magnets. According to the invention an operating magnet is provided to be operated by said current impulses or current break, the system being arranged so that, over field contacts, closed by indication of an actuated selecting magnet, a succeeding selecting magnet is energized; the indicating member of said selecting magnet is set in indicating position below the respective field contact group when the operating magnet thereafter is released so that the operating magnet, on its repeated operation, operates the field contact group which, over its field contacts, closes a circuit for operation of a succeeding selecting magnet, and so on. Other characteristics of the invention are seen from the following description.

To clearly understand the invention it is necessary to observe that, when an operating bar in a cross bar switch is actuated, the selecting members (fingers) on the selecting bars cannot be inserted below the contact spring groups on said operating bar but rest, if moved, resiliently against a lifting spring or corresponding member belonging to the respective contact spring group, until the operating bar is released.

The invention will hereinafter be more closely

described with reference to attached drawings. Figs. 1, 2 and 3 show two embodiments thereof for numerical setting, for instance, in group or final selectors.

5. In Fig. 1, STM₁—STM₄ are the selecting magnets in a cross bar switch, of which only is shown the supplementary operating magnet HBRM for successive operation of the selecting magnets STM₁—STM₄. IMR is an impulse indicating relay; TBR a slow-operating so-called blocking relay, STR a relay for disconnection of the first operated selecting magnet STM₁ and IVR an impulse controlling relay. All these relays have functions known per se. HR₁ and HR₂ are supplementary relays for the bar setting. The diagram is simplified, only the circuits and switching elements required for a clear understanding of the invention being shown.

- The system operates principally as follows. 20. At a call on line L, the impulse indicating relay IMR is operated, whereby a magnetization circuit for relay TBR is closed over make in the switching contact 1—IMR. When the first current interruption takes place, relay IMR is released, while the relay TBR in known manner is slow releasing and thus not released until the switching operation is completed. On relay IMR releasing, a circuit is completed from positive over make contact 1—TBR, break contact 1—STR, winding on selecting magnet STM₀ and winding on relay HR₁ to negative, whereby STM₀ and HR₁ are actuated. From positive in the make contact 2—TBR a circuit is now completed in make contact 1—HR₁ over winding 1—HBRM to negative. 35. Consequently, the operating magnet HBRM is operated. A circuit is completed in contact 1—STM₀ for relay IVR, which is not operated, being short-circuited at contact 2—IMR over switching contact 1—IVR. At contact 1—HBRM a circuit is completed for relay STR which, at its contact 1, breaks the initial magnetization circuit for selecting magnet STM₀ which now receives holding current over contact 3—STM₀. Relay STR receives holding current over contact 2—STR so as not to operate on release of the operating magnet HBRM during reception of the impulse train. At contact 2—STM₀ a magnetization circuit is further prepared for the selecting magnet STM₁. When the relay IMR is again magnetized at the 50 termination of current break, relay IVR is operated by current in its winding 1, the short-circuiting at contact 2—IMR now being removed. Contact 2—HBRM guarantees the operation of operating magnet HBRM before relay IVR operates which is obtained by the last-mentioned

relay being short-circuited at said contact 2—HBRM when the operating magnet HBRM is non-energized. When relay IMR at the following current break is again deenergized relay IVR receives holding current through its winding II over contacts 1—IVR, 2—IMR and 2—TBR. The selecting magnet STM₁ and, in series with it, relay HR₂ are now energized over contacts 1—IMR, 1—TBR, 2—IVR and 2—STM₀. The operating magnet HBRM being operated, indicating member on selecting bar of selecting magnet STM₁ cannot be inserted below the field contact group but rests at the moment resiliently against the lifting spring or corresponding member below said field contact group. The magnetization current for the operating magnet HBRM is now interrupted at the make-and-break contact 1—HR₂ and when the operating magnet is released the circuit for selecting magnet STM₀ and relay HR₁ at contact 3—STM₀ is interrupted. The selecting magnet STM₁ and relay HR₂ remain in operated position as they receive holding current over contacts 3—IVR and 2—HR₂ and resistance R₁. The resistance value of resistances R₁—R₄ is selected so that the respective selecting magnets are not operated by current therethrough but only held in operated position after once having received more powerful make current. Indicating device on the bar of the selecting magnet STM₁, by its elastic force, penetrates under the respective multiple contact group.

On release of relay HR₁ a circuit is completed for winding II—HBRM over contacts 2—TBR, 1—HR₂ and 3—HR₁. Thus the operating magnet HBRM is again operated, thereby operating the field contact group corresponding to selecting magnet STM₁. By the field produced by winding II—HBRM having inverse direction to the field from winding I—HBRM, full guarantee is given that the operating magnet is released completely during the brief period of time both these windings are de-energized, since inversion of the field takes place. At contact 2—STM₁ a make circuit is prepared for selecting magnet STM₂ and at contact 3—STM₁ a holding circuit for selecting magnet STM₁ is closed. When relay IMR is again magnetized the holding circuit at contact 2—IMR is broken for relay IVR which is then released. At the following release of relay IMR the magnetization circuit for selecting magnet STM₂ and relay HR₁ at contact 1—IMR over contacts 1—TBR, 2—IVR and 2—STM₁ is formed. When relay HR₁ operates a holding circuit is closed for selecting magnet STM₂ and relay HR₁ over contacts 3—IVR and 2—HR₁ and resistance R₂. Furthermore, the circuit for winding II—HBRM at contact 3—HR₁ is interrupted and selecting magnet STM₁ and relay HR₂ are released when contact 3—STM₁ is broken on release of operating magnet HBRM. The winding I—HBRM is energized over contacts 2—TBR, 1—HR₂ and 1—HR₁ whereby operating magnet HBRM is again operated. The operation described above is repeated if further impulses arrive on the line L.

In a system according to Fig. 2 the supplementary relays HR₁ and HR₂ shown in Fig. 1 are dispensed with.

At first, as in the system shown in the foregoing figure, the relays IMR and TBR are energized. When relay IMR releases at the first current break, a circuit is completed for selecting magnet STM₀ at contact 1—IMR over contacts 1—TBR and 1—STR. At the same time a make circuit for relay STR₁ at contact 2—STR is closed. Re-

lay STR has a longer make time than selecting magnet STM₀ so as to guarantee its closing before its make circuit is broken at contact 1—STR. Selecting magnet STM₀ remains operated by a circuit over resistance R₁ and contacts 1—STR and 2—TBR. Relay STR receives holding current over contacts 2—STR and 3—TBR, thus remaining operated until termination of the switching operation. On relay STR closing, a circuit is formed at contact 3—STR over contacts 1—IMR, 1—TBR and 2—IVR for winding I on operating magnet HBRM which operates and receives holding current over field contact 1—STM₀. A circuit is prepared for selecting magnet STM₁ at contact 2—STM₀ and a holding circuit is closed for selecting magnet STM₁ at contact 3—STM₀. At contact 4—STM₀ a circuit is closed for winding I on relay IVR, which is however kept short-circuited over contacts 3—IVR, 2—IMR and 2—TBR as long as relay IMR is non-energized. When the latter relay on termination of current break operates again, the make circuit is broken for winding I—HBRM and the short-circuiting of relay IVR is removed, said relay thus operating. At the following release of relay IMR the relay IVR receives holding current through its winding II over contacts 3—IVR, 2—IMR and 2—TBR and a circuit is completed for winding Ü on operating magnet over contact 1—IMR, 1—TBR, 1—STR and 2—IVR. When the current over winding II—HBRM is more powerful than the holding current over winding I—HBRM and when the windings counter-act each other, a field inversion occurs in operating magnet HBRM which is thus released and thereupon operates anew. During the time the operating magnet HBRM has non-energized position, the holding circuit is broken for selecting magnet STM₀ at contact 3—STM₀ and the indicating member is inserted into the selecting bar corresponding to the selecting magnet STM₁ under the respective field contact group. Selecting magnet STM₁ is kept operated by current over contacts 2—TBR, 1—IVR and resistance R₂. Further, a circuit is closed for operating magnet HBRM winding II over contacts 1—HBRM, 3—STR and 2—IVR. Contact 1—HBRM has for an object to guarantee the closing of the operating magnet, even if relay IMR should be operated before the operating magnet has had time to operate again, thus rendering the system independent, to a certain extent, of the impulse condition of the impulse train. When the operating magnet HBRM operates the field contacts of selecting magnet STM₁ are closed. Over contact 1—STM₁ the operating magnet HBRM receives holding current. Over contact 2—STM₁ a circuit is prepared for selecting magnet STM₂ and, finally, at contact 3—STM₁ a holding circuit is closed for selecting magnet STM₁. When the relay IMR again is closed the circuit at contact 2—IMR is broken for winding II on relay IVR, which is released. At the now following release of relay IMR a circuit is again completed for winding I—HBRM so that field inversion takes place in the operating magnet HBRM whereupon the operation is similar to the previously described operation. Contact 2—HBRM serves to prevent relay IVR from operating or relapsing respectively during the time the operating magnet HBRM is released. In Fig. 3 magnets STM₀, STM₁ etc. are selecting magnets in a crossbar switch, the operating magnets of which are termed BRM₀, BRM₁ and BRM₂. Each contact field of the operating magnet contains three contact strips S₁, S₂ and S₃.

5

Contact field of operating magnet BRM_0 contains further a fourth such strip S_4 . The a - and b -wires of incoming line L_1 are connected in parallel to strips S_1 and S_2 respectively in all the operating magnets. The outgoing lines are connected to the individual contacts on respective operating magnet in such a way that their a - and b -wires on operation of a certain field contact group over respective strips S_1 and S_2 are connected to incoming line L_a , and their c -wires over the respective strip S_3 to test devices. The outgoing lines which are connected to field contacts corresponding to the same selecting magnet form a numerical route within which nonnumerical selection can take place. Amongst the outgoing lines only one, L_a , is shown in the figure.

The relay set of the group selector is composed of a test relay LYR , an impulse indicating relay JMR , a slow-acting so-called cut-out relay TBR , a number indicating relay SMR and a relay STR for disconnection of the first operated selecting magnet STM_0 .

The system operates principally as follows:

When the group selector is called, the circuit for the impulse indicating relay JMR is closed in known manner over line L_1 . On closing of relay JMR the make circuit for relay TBR at contact 1— JMR is closed, said relay being slow releasing so that it remains attracted although relay JMR is released and attracted in time to the numerical impulses. When relay TBR is attracted a circuit is completed over contacts 3— TBR , 1— BRM_0 and 4— STR for selecting magnet STM_0 which is operated. On relay JMR being released at beginning of the first impulse a further circuit is closed over contacts 2— JMR , 1— TBR and 1— STR for relay SMR which thus operates. At contact 1— SMR the strip S_4 is connected to positive potential.

When the relay JMR at the termination of the impulse is attracted again, relay STR is energized by current through its winding I over contacts 1— JMR and 2— SMR . The make circuit for selecting magnet STM_0 is broken at contact 4— STR and, for relay SMR , at contact 1— STR . Both remain however attracted, the selecting magnet STM_0 for holding current over resistance r_0 and relay SMR due to delayed action. It is to be observed that the resistances r are so dimensioned that the selecting magnets are not operated in series therewith, but receive sufficient current to remain actuated when once in operated position.

When now, at beginning of the second impulse the relay JMR is released the make circuit for operating magnet BRM_0 is closed at contact 1— JMR over contacts 4— SMR and 2— STR and over the contacts 1— BRM_2 and 1— BRM_1 (contacts in the side spring groups of the operating magnets) connected in series. Operating magnet BRM_0 is thus operated. Simultaneously relay SMR receives a new magnetization impulse over contacts 2— JMR , 1— TBR and 3— SMR . When the operating magnet BRM_0 operates, winding on selection magnet STM_1 is connected to strip S_4 causing operation of said selecting magnet. Since operating magnet BRM_0 already is operated the indicating member of said selecting magnet is not inserted below the contact spring group in question, but rests resiliently against the lifting spring available in the contact spring group or against a corresponding member. When the operating magnet BRM_0 operates the make circuit for selecting magnet STM_0 is broken at contact 1— BRM_0 so that said selecting magnet is released.

6

When now, at termination of the second impulse relay JMR is again attracted, the circuit for operating magnet BRM_0 is broken at contact 1— JMR causing said operating magnet to be released. Although the make circuit for selecting magnet STM_1 is broken at the field contact in the field contact group corresponding to the selecting magnet STM_0 which field contact cooperates with strip S_4 , the selecting magnet STM_1 still remains actuated, since it receives holding current over contact 1— BRM_0 and resistance r_1 . Thus its indicating member is inserted below the corresponding field contact group. Over contact 1— JMR the relays TBR and STR receive a new magnetisation impulse.

The operation at further incoming numerical impulses is entirely similar to the above described operation wherefore any further description hereof may not be necessary.

After termination of the last numerical impulse the relay JMR remains closed, causing relay SMR to be released as soon as the opening time at contact 2— JMR has reached the value necessary for release of relay SMR . Relay STR is not released hereby but receives holding current over its contact 3. At contact 1— SMR the make circuits are broken for selecting magnets STM_0 wherefore the hereupon following operation of the operating magnet BRM_0 does not cause any selecting magnet to operate. The last operated selecting magnet hereafter remains operated irrespective of the position of the operating magnet BRM_0 since it receives holding current over contacts 6— SMR and 4— STR . The operating magnet BRM_0 is energized anew by current over contact 5— SMR . Its operation initiates a rush movement during which operating magnets BRM_1 successively operate until a free line in the numerical route appointed by the operated selecting magnet is found. The selection takes place as follows.

By operation of the operating magnet BRM_0 the c -wire of the respective outgoing line is connected over contact 3— BRM_1 , holding II— STR and contact 1— SMR to winding on test relay LYR . Presuming that the line is now engaged, the relay LYR is not energized. On operation of operating magnet BRM_1 the make circuit for operating magnet BRM_1 is immediately closed over contacts 3— LYR , 2— TBR , 8— SMR and 2— BRM_0 . On operation of BRM_1 the test relay LYR is disconnected from the test conductor of the connected line in order to prevent testing to take place on said line after operation of the operating magnet BRM_1 . The circuit for operating magnet BRM_1 is now broken at contact 1— BRM_1 where instead a holding circuit is closed for BRM_1 . The test conductor of the now connected line is connected to test relay LYR over contact 3— BRM_2 the operation of which is similar to that of contact 3— BRM_1 . The successively performed operation and release of the operating magnets continues identically till a free line is found. Hereby the test relay LYR is actuated in known manner, the make time of which is briefer than the make time for the operating magnets. The selection time is now stopped by break of a rush circuit at contact 3— LYR whereby the incoming line L_1 is connected to the respective outgoing line L_a at contacts 1— LYR and 2— LYR . Although relay IMR releases relay STR is energized by current through its holding winding II in series with test relay LYR . By the permanent release of relay JMR the relay TBR also releases. When the c -wire of the out-

going line L_a is de-energized by releasing of the communication the relays LYR and STR are released and thus also the operated operating magnet BRM, the holding circuit of which is broken at contact 2—STR.

The above described embodiments are only to be considered as examples to give a more clear understanding of the invention. The invention naturally allows of many variations and modifications without the principle of invention thereby being infringed upon.

We claim:

1. In an automatic telephone system, a cross bar switch and an impulse relay, said cross bar switch including selecting magnets and an operating magnet, an operating bar actuated by the said operating magnet, one contact set on said operating bar for each selecting magnet, one contact in each of said contact sets, when actuated, closing a circuit for energizing a succeeding selecting magnet, means for energizing one of said selecting magnets, means for energizing said operating magnet in dependence upon an impulse from said impulse relay to actuate the contact set for the energized selecting magnet, means for operating said succeeding selecting magnet, means for releasing the first and holding the last energized selecting magnet upon said operating magnet being released and thereafter energized by another impulse from said impulse relay.

2. In an automatic telephone system, a cross bar switch and an impulse relay, said cross bar switch including selecting magnets and an operating magnet, an operating bar actuated by the said operating magnet, one contact set on said operating bar for each selecting magnet, one contact in each of said contact sets, when actuated, closing a circuit for energizing a succeeding selecting magnet, means for energizing one of said selecting magnets by an impulse from said impulse relay, means for energizing said operating magnet in dependence upon said impulse to actuate the contact set for the energized selecting magnet, means for operating said succeeding selecting magnet by the next impulse, and means for releasing the first and holding the last energized selecting magnet upon said operating magnet being released by said next impulse.

3. In an automatic telephone system, a cross bar switch and an impulse relay, said cross bar switch including selecting magnets and an operating magnet, an operating bar actuated by the said operating magnet, one contact set on said operating bar for each selecting magnet, one contact in each of said contact sets, when actuated, closing a circuit for energizing a succeeding selecting magnet, means for energizing one of said selecting magnets, means for energizing said operating magnet, in dependence upon an impulse from said impulse relay to actuate the contact set for the energized selecting magnet, means for operating said succeeding selecting magnet, means for releasing the first energized selecting magnet, when said operating magnet is energized by said impulse, and for holding the said succeeding selecting magnet after the termination of said impulse.

5 10 15 20 25 30 35

4. In an automatic system as described in claim 2, two circuits for actuating the operating magnet, controlled by said impulse relay, a winding for the operating magnet in each of said circuits, said two circuits energizing the operating magnet in opposite directions, means changing said two circuits at the beginning of each impulse from said impulse relay.

5. In an automatic system as described in claim 2, two circuits for actuating the operating magnet, controlled by said impulse relay, a winding for the operating magnet in each of said circuits, said two circuits energizing the operating magnet in opposite directions, means changing said two circuits after the end of each impulse from said impulse relay.
